POLE SCAFFOLD

Algol Strom, Juneau, Alaska, assignor of one-half
to J. Arch Bulger, Juneau, Alaska

Application November 25, 1935, Serial No. 51,509

5 Claims. (Cl. 304—28)

This invention relates to pole scaffolds.

The primary object of the present invention is to provide a scaffold adaptable to be detachably engaged to round steel or wooden poles by a pair of pole encircling chains, the upper chain producing a self-tightening effect as weight is applied to the platform or scaffold.

Another feature of the present invention is a chain tightening mechanism carried by the frame of the scaffold which permits one of the chains to be tightened or loosened at will.

Further objects of the invention are to provide a device of the character referred to that is strong, compact and durable, thoroughly reliable for each intended purpose, very easy to attach and detach from a pole and that is comparatively inexpensive to manufacture.

With the foregoing and other objects in view the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereunto appended.

In the drawings wherein like reference characters denote corresponding parts throughout the several views:—

Figure 1 is a fragmentary elevation of a portion of a pole showing an adaptation therewith of the device in accordance with the present invention and having parts of the device broken away.

Figure 2 is a top plan view of the device partly broken away and removed from the pole.

Figure 3 is a vertical section through the frame of the device taken substantially on the plane of line 3—3 of Figure 2.

Figure 4 is a front elevation of the frame.

Figure 5 is a rear elevation of the frame.

Figure 6 is an enlarged fragmentary side elevation of the frame and an axial detailed section through the chain adjusting means.

Figure 7 is a detailed diametric section taken substantially on the plane of line 7—7 of Figure 6.

Figure 8 is a detailed longitudinal section in detail through the chain adjusting means showing the ratchet dog operating means.

Referring to the drawings in detail the frame A is shown attached to a round vertical pole B which pole may be either wood or metal. The frame is preferably made of a casting such as

steel. The frame A is formed of a pair of companion side rails 10, 11 which extend in spaced parallel relation.

The lower ends of the side rails merge with an outwardly bowed bottom rail 12. The upper ends of the side rails 10, 11 are curved outwardly as indicated at 13 and particularly shown in Figure 3 of the drawings. On the outside of the curved portion 13 of the rail 10 is an anchoring cleat 14, while there is a like cleat 15 on side 10 rail 11 in alignment with cleat 14. On the confronting faces of the jaws of the cleats 14, 15 are gripping ribs 16 which ribs anchor between the links on the opposite end portions of the upper or safety chain 17, and the intermediate portion of the chain encircles and grips the pole.

The casting of the frame A is further formed with an arched member indicated generally at 18 which bridges an intermediate portion of the side rails nearly in the center thereof. This arch member 18 is bowed outwardly so that the inner face thereof has gripping engagement with a segment of the circumference of a pole. There is a dove-tailed pocket 19 on the inner face of the arch member which extends from the upper edge substantially one half of the width thereof. In this pocket 19 fits a plate 20 that permits the frame to be attached to a right-angled object, construction, or position. On each side of the pocket 19 are spaced vertically extending parallel ribs 21, 22 and between the parallel ribs and the pocket 19 are curved ribs 23. The curved ribs or corrugations prevent downward slipping, of the frame A, while the vertical parallel ribs prevent side slipping on either steel or wooden poles. In each rail 10, 11 extending from the inner edge thereof are wooden spurs 24 that detachably seat in sockets 25 formed in the rails.

Extending rearwardly from the rear face of the arch member 18 of the frame are a pair of spaced bars 26, 27. The space between the bars 26, 27 provides a pocket to receive the inner end of the scaffold board or platform board 28 and this board is secured to the bars by means of the bolts 29.

On an intermediate portion of one side rail 10 and on the outside thereof is a cleat 30. This cleat 30 is similar in all respects to the cleats 14, 15 and has ribs on the confronting faces of the jaws thereof which engage between the links at the one end of the lower or binding chain 31. The binding chain 31 is adjustable to tighten or loosen the same from pole encircling relation and for this purpose there are a pair of horizontally

spaced bosses 32, 33 on the outside of rail 11 in alignment with the arch member 18. In each lug is a smooth bore which is aligned with the other. There is a bolt 34 coupled to the one end 5 of the lower or binding chain 31 as at 35. The threaded shank 36 of the bolt 34 extends through the smooth bores in bosses 32, 33 in slidable relation and on an intermediate portion of the threaded shank is threadably engaged an annular ratchet member 37. Around the center of the outer periphery of the ratchet member 37 are the continuous series of ratchet teeth 38. To operate the ratchet member 37 and screw the bolt 34 in or out for tightening the binding chain 31 10 15 is a ring 39 rotatably mounted on the smooth outer margins of the ratchet member 37. Around the center on the inside periphery of member 39 is an annular cavity 40 and the teeth 38 are free to move in this cavity. In one side of the cavity 20 25 40 is an inset recess 41 and in this recess 41 is pivoted a forked ratchet dog having opposed prongs 42, 43. One or the other of the prongs engages the teeth 38 depending upon whether bolt 34 is tightening or loosening chain 31. So as to permit the dog to rock, the center is fixed to a pivot 44 journaled in the opposite side walls of the cavity 41. Merging with the cavity 41 is a pocket 45 and in this pocket is a helical over-center spring 46. The outer end of this coil 30 35 40 spring 46 bears against the wall of the pocket 45 and the inner end thereof embraces a lug on the outside of the ratchet dog at a point in alignment with the pivot 44 so that when either one or the other of the prongs are engaged with ratchet teeth the spring holds the same engaged, because in engaged position the axis of the spring is disposed at an angle. This construction of the forked dog with the pivot and spring arrangement permits a ratchet movement when tightening 45 50 the binding chain 31, or when the binding chain 31 is being loosened. From the outer periphery of the ring member 39 extends the operating handle 47. One end of pivot pin 44 has a crank 44a that extends on the outside of the ring member 39 and moves in a pocket 44b. By swinging crank 44a to either end of its arc either one or the other of the prongs on the ratchet dog are brought into engagement with teeth 38 where they are retained in the engaged relation 55 by the spring 46.

In attaching the device of the present invention to a pole the safety chain 17 is attached first. So as to obtain a tight fit about the pole the frame is rocked inwardly on the curved portion 13 of the side rails. By rocking the frame inwardly a tight fit is accomplished when the links are slipped into the upper cleats 15, 16. Then the lower or binding chain 31 is attached by slipping the link on the free end of the binding chain into the cleat 30. This being done, handle 47 is turned whereupon the bolt moves outwardly thereby tightening the binding chain 31 and bringing the frame into tight gripping relation with a portion of the periphery of the pole. The chains 17 and 31 encircle the pole in parallel relation. To remove the device handle 47 is turned so that the bolt moves inwardly and when the binding chain 31 is loose the links may be slipped from the cleat 30. The upper chain 70 75 17 may then be removed from the engaging cleats 14, 15.

Having described my invention, what I claim is:

1. In combination with a pole scaffold characterized by a pole embracing frame a scaffold

board carried by the frame, and a pole encircling chain carried by the frame of means for adjusting one end of the chain comprising a pair of spaced apertured bosses carried by the frame, a bolt connected to one end of the chain and having a threaded shank slidable in bosses, a ratchet gear formed with smooth portions on the margin of the periphery with teeth in between and threadedly mounted on an intermediate portion of the shank between the bosses, an operating member formed of a ring slidable on the smooth portions of the ratchet gear having a handle extending from the ring, and a rockable ratchet dog in the ring. 5 10 15

2. In combination with a pole scaffold characterized by a pole embracing frame a scaffold board carried by the frame, and a pole encircling chain carried by the frame of means for adjusting one end of the chain comprising a pair of spaced apertured bosses carried by the frame, a bolt connected to one end of the chain and having a threaded shank slidable in the said bosses, a ratchet gear formed with teeth in the center and smooth portions on the margins of the periphery and threadedly mounted on an intermediate portion of the shank between the bosses, an operating member formed of a ring slidable on the smooth portions of the ratchet gear having a handle extending from the ring, a rockable ratchet dog in the ring, and said ratchet dog being forked and having a pair of oppositely extending prongs one of which is engaged with the ratchet teeth while the other is free. 20 25 30 35

3. A pole scaffold, and in combination, a frame for bearing contact with a portion of the periphery of a pole only, said frame equipped with elongated parallel side rails having bearing contact in an axial direction on the pole, an arch member connecting intermediate portions of the rails and having bearing contact in a circumferential direction on a segment of the pole between the side rails, means carried solely by the arch member for anchoring platform boards to the frame, said side rails having portions at one end curved outwardly to provide a fulcrum to rock the curved ends of the rails inwardly, cleats carried by the rails situated at the curved end of the rail so that rocking movement will change the length of an arc between the curved ends, and a chain detachably seated in the cleats and girdling the remaining portions of the pole whereby the scaffold is secured to the pole. 40 45 50 55

4. A pole scaffold, and in combination, a frame for bearing contact with a portion of the periphery of a pole only, said frame equipped with elongated parallel side rails having bearing contact in an axial direction on the pole, an arch member connecting intermediate portions of the rails and having bearing contact in a circumferential direction on a segment of the pole between the side rails, means carried solely by the arch member for anchoring platform boards to the frame, said side rails having portions at one end curved outwardly to provide a fulcrum to rock the curved ends of the rails inwardly, cleats carried by the rails situated at the curved end of the rail so that rocking movement will change the length of an arc between the curved ends, a chain detachably seated in the cleats and girdling the remaining portions of the pole whereby the scaffold is secured to the pole, a second pole girdling chain, and means carried by intermediate portions of the side rails for attaching the second chain to the frame. 60 65 70 75

5. A pole scaffold, and in combination, a frame

for bearing contact with a portion of the periphery of a pole only, said frame equipped with elongated parallel side rails having bearing contact in an axial direction on the pole, an arch 5 member connecting intermediate portions of the rails and having bearing contact in a circumferential direction on a segment of the pole between the side rails, means carried solely by the arch member for anchoring platform boards to 10 the frame, said side rails having portions at one end curved outwardly to provide a fulcrum to rock the curved ends of the rails inwardly, cleats

carried by the rails situated at the curved end of the rail so that rocking movement will change the length of an arc between the curved ends, a chain detachably seated in the cleats and girdling the remaining portions of the pole whereby 5 the scaffold is secured to the pole, a second pole girdling chain, means carried by intermediate portions of the side rails for attaching the second chain to the frame, and said attaching means being adjustable.
